(57) **CLAIM**

The ornamental design for a shelf as shown and described.

DESCRIPTION

FIG. 1 is a perspective view of a shelf.
FIG. 2 is a side view of the shelf of FIG. 1.
FIG. 3 is a front view of the shelf of FIG. 1.
FIG. 4 is a rear view of the shelf of FIG. 1.
FIG. 5 is a top view of the shelf of FIG. 1.
FIG. 6 is a perspective view of another shelf.
FIG. 7 is a side view of the shelf of FIG. 6.
FIG. 8 is a front view of the shelf of FIG. 6.
FIG. 9 is a rear view of the shelf of FIG. 6.
FIG. 10 is a top view of the shelf of FIG. 6.
FIG. 11 is a perspective view of another shelf.
FIG. 12 is a side view of the shelf of FIG. 11.
FIG. 13 is a front view of the shelf of FIG. 11.
FIG. 14 is a rear view of the shelf of FIG. 11.
FIG. 15 is a top view of the shelf of FIG. 11.
FIG. 16 is a perspective view of another shelf.
FIG. 17 is a side view of the shelf of FIG. 16.
FIG. 18 is a front view of the shelf of FIG. 16.
FIG. 19 is a rear view of the shelf of FIG. 16; and,
FIG. 20 is a top view of the shelf of FIG. 16.
The broken lines show portions of the shelf that form no part of the claimed design.

1 Claim, 16 Drawing Sheets
